UNITED STATES PATENT OFFICE

EDWARD J. FOWLER, DECEASED, LATE OF REDWOOD CITY, CALIFORNIA, BY EDITH MARY FOWLER, EXECUTRIX, OF REDWOOD CITY, CALIFORNIA, AND DUDLEY BAIRD, OF BERKELEY, CALIFORNIA, ASSIGNEES TO NICHOLS COPPER COMPANY, OF NEW YORK, N. Y., A CORPORATION OF NEW YORK

MULTIPLE HEARTH FURNACE

Application filed March 8, 1928. Serial No. 260,032.

This invention relates to multiple hearth roasting furnaces and more particularly to methods and means for controlling temperature conditions at the various hearths of such furnaces. Also the invention as to certain of its phases relates to the construction and operation of furnaces having a substantially greater number of hearths than has heretofore been embodied in furnaces of this general type.

The objects of the invention include the provision of furnace constructions of the class indicated, and also methods of operating such furnaces, which will be dependable, relatively simple and efficient under various conditions, and in which the treatment of various kinds and grades of material may be accurately controlled.

Various further and more specific objects, features and advantages will clearly appear from the detailed description given below taken in connection with the accompanying drawings which form a part of this specification and illustrate merely by way of example one embodiment of the apparatus of the invention.

The invention consists in such novel features, arrangements and combinations of parts as may be shown and described in connection with the furnace herein disclosed by way of example only and as illustrative of a preferred embodiment, together with such novel methods and steps of processes as may be described herein.

The drawing comprises a vertical sectional view, partly broken away, through a furnace comprising one embodiment of the invention.

The furnace as illustrated may be of the same general class as that shown in numerous patents to J. B. F. Herreshoff, as for example No. 976,175 of November 22, 1910, and may incorporate if desired various improvements such as for example the improved shaft and rabble arm construction shown in the copending application of Dudley Baird, Ser. No. 140,230, filed October 8, 1926.

A plurality of vertically spaced or superposed hearths is indicated and designated respectively by the numerals 1 to 12. These

hearths may be surrounded and supported in the conventional manner as by a cylindrical furnace wall 13. A rotatable and internally cooled central shaft 14 extends vertically up through the center of the furnace and is provided with rabble arms as at 15 and 16. In the embodiment shown, two oppositely directed rabble arms are provided to cooperate with each hearth area in the usual manner. Suitable rabble teeth as at 17 are provided along each of the rabble arms for advancing the material being treated successively over each hearth down through the furnace.

While in the drawing, 12 hearths only are indicated for simplicity, it will be understood that various features of the invention are applicable alike to furnaces having a number of hearths in the neighborhood of 12 and to furnaces having a substantially larger number of hearths, for example as many as 25.

The central shaft 14 as here illustrated, may be provided with an internal conduit as at 18, the rabble arms being also provided with inner conduits of any desired well known form communicating with the conduit 18, whereby cooling fluid such as air carried by the conduit 18 may be allowed to pass through the conduits of the various rabble arms, and thence back into an annular space 19 between the conduit 18 and the walls of the shaft 14. The cooling fluid for example may be introduced through the usual adjustable damper intake at the end 85 of the conduit 18 at the bottom of the furnace and the same fluid or a portion thereof, after having circulated through the various rabble arms, may be discharged from the top of the shaft 14 as through an adjustable 90 damper 20.

At various of the hearths, or if desired at all or substantially all of the hearths, the shaft 14 may be provided with sockets or attaching means as at 21 designed to receive 95 heat absorbing or radiating arms as at 22. The sockets 21 as shown may be conveniently located intermediate the rabble arms 15 and 16. The radiating units 22 may be made communicative through the sockets 21 with 100

the cooling fluid conduit 18 at their inlet ends and with the annular space 19 at their outlet ends, whereby a circulatory path is provided through the radiating units, thus permitting control or alteration of the temperature conditions on hearths which are provided with such radiating means. In certain processes it may be desirable to maintain some of the hearths at a relatively low temperature, or combustion conditions may be such as to require a considerable cooling effect on certain hearths. This may be generally accomplished by using one or two of the radiating units as at 22 over such hearths, or if these prove insufficient to accomplish the desired cooling, either a greater number of these units may be applied at each hearth, or similar but larger units as at 23 may be used. As indicated at 21', the supporting sockets for the radiating arms may be more or less closely spaced so as to provide for the desired number of arms at each hearth. Although the radiating arms as here shown comprise a single conduit, it will be understood that various other forms and shapes of radiating units might be utilized to secure the desired cooling effect. Also it will be understood that the invention is applicable equally to various furnace constructions well known in the art, having central shaft arrangements other than the particular double concentric wall construction shown.

If for particular processes it is found to be unnecessary to use radiating units as above described at certain hearths, the socket provisions such as at 21 may be still provided for manufacturing convenience and standardization of shaft parts, the unused sockets being then covered either temporarily or permanently by cover plates as at 24.

At other hearths, the lowermost hearths for example, it will not only be found to be undesirable to provide cooling means with many processes, but the efficiency of the furnace may be improved by raising the temperature at such hearths. For this purpose "hot air arms" as at 25 may be provided to fit, if desired, sockets such as at 21 interchangeably with the radiating units, so that sections of the shaft 14 may be standardized and still have provision for either type of arm. The "hot air arms" 25 are made communicative with the annular space 19 so as to discharge a part of the air therefrom directly on to the material under treatment at the hearths. The air or other fluid medium thus discharged will of course be preheated to a considerable extent by reason of having previously passed through the radiating unit and the rabble arm cavities. A convenient means is therefore provided for reducing the temperature on certain hearths to the extent desired and for transferring the heat thus acquired in the cooling me-

dium, to other hearths where the efficiency of operation may be enhanced by an increase over the temperature which would otherwise prevail. If desired, for certain roasting operations the furnace temperatures at the various hearths may be substantially equalized in this manner.

When "hot air arms" as at 25 are used in lieu of radiating units at the sockets 21, the openings communicating with the interior shaft conduit 18 may be closed off as by plugs as at 26; similar plugs of course may also be used whenever the plates 24 are necessary.

In some instances it is desirable to provide at certain hearths, particularly at the lower hearths, a greater amount of preheated air than can be admitted by the arms 25. In that event, one of the rabble arms at such hearths may be replaced by a relatively large "hot air arm" as at 27.

To achieve efficient roasting conditions, it is generally desirable to locate the openings of the arms 25 at points where the preheated air will engage the falling material as it passes from one hearth to the next. For example, the arms 25 at hearth #10 may be placed so that the preheated air impinges directly upon the material dropping from the hearth #9 through the central hearth opening 28. The arms 27 if desired, may be somewhat larger and longer than the arms 25 so as to widely distribute the preheated air over the hearth areas.

As to the design and constructional details of other parts of the furnace not specifically referred to herein, the usual practice may be followed as in the construction of other well known furnaces of this general type.

The above described radiating or heat absorbing arms are particularly useful in many roasting operations when placed at the intermediate hearths, since there is often a tendency for the intermediate hearths to become overheated as a result of the rapid chemical actions taking place in the materials under treatment when they arrive at the mid-portion of the furnace. On the other hand, as the ores or other materials arrive at the lower hearths of the furnace, there is often a tendency for the temperatures to become too low to insure thorough treatment, inasmuch as the heat of oxidation will usually be less at the lower hearths, the material having been previously exhausted of most of its combustible or oxidizable substances in the upper or intermediate hearths. This invention therefore provides a convenient means for transferring the excess heat of the intermediate hearths to the lower hearths where such heat is often needed to give the ores or other material a complete and final roasting.

The heat absorbing arms embodying this invention should of course be clearly distinguished from the mere use of air cooled rabble arms in which the function of the cir-

culated air is to merely maintain the rabble arms and teeth at temperatures which will prevent their deterioration or distortion. While the rabble arms at the various hearths 5 may ordinarily be made substantially alike as to form, number and arrangement, in order to insure a uniform flow through the furnace of the material under treatment, on the other hand the heat absorbing arms at 10 each hearth may, of course, be made independent of such arms on the other hearths, as to form, number, and arrangement. The cooling arms provide a cooling effect substantially in excess of any normal cooling 15 effect arising from the use of the usual air cooled rabble arms, since the heat absorbed from the furnace through the necessarily relatively thick walls of the rabble arms is small as compared with the heat which may be 20 transferred through cooling arms as at 22 designed particularly for that purpose.

Although for convenience and for obtaining substantial uniformity of cooling effects throughout the area of the hearths it is desirable to arrange the rabble arms and cooling arms alternately as shown, it will be understood that approximately equivalent results might be obtained by other arrangements or by providing the radiating units as 30 substantially unitary structures in conjunction with the rabble arms.

According to this invention, the circulating cooling fluid serves as many as three functions; namely, the necessary cooling of 35 the rabble arms and shaft is accomplished, temperature conditions throughout the furnace may be equalized or controlled with a wide range of flexibility, and a source of preheated air is provided at certain hearths 40 for insuring a very effective supply of oxidizing fluid sufficient for proper completion of the roasting processes. At the same time the heat available throughout the furnace is economically utilized.

45 In recent times it has become the practice with furnaces of this general type to treat materials embodying large quantities of finely divided flotation concentrates. Because of their fineness such mixtures often 50 do not oxidize readily on the hearths; there being few voids in such fine material, the oxidizing action tends to become smothered. We have found that this effect may be overcome in a desirable manner by providing a 55 substantially larger number of hearths with a consequent correspondingly large number of "material drops" or places where the material drops from one hearth to the next through the ascending hot oxidizing gases. 60 At these "material drops" the multitudes of finely divided particles have ample opportunity for sufficient contact with the oxidizing gases notwithstanding the degree of fineness of the material. However, as the number 65 of hearths is increased, the control of

temperature conditions throughout the furnace becomes more difficult, but any difficulties in that respect may be readily met by the heat transferring means provided in the manner above described. With many roasting operations it is desirable to provide relatively cool hearths at the top of the furnace (the top four or six hearths for example), and also a number of relatively cool hearths at the very bottom of the furnace, (as many 70 as four or six hearths) and this is ordinarily permissible only where the number of hearths is increased to in the neighborhood of 12 or more. According to our invention these cooler hearths may be maintained at temperatures in the neighborhood of 800° F. to 75 1000° F. for example.

On the other hand, in certain roasting operations as above indicated, it is desirable to have hot discharge calcines and in connection 80 with acid manufacture, particularly chamber acid, it is desirable to have a hot gas discharge and cool cinder discharge. With some sulphide ores the free sulphur ignites at the top hearth, resulting in high temperatures at the upper hearths. It is obvious, however, that a furnace with a large number of hearths as above described, particularly if equipped with the heat absorbing arms and hot air arms, will permit operating 85 conditions satisfactory for all of these various processes and at the same time provide a sufficient number of "material drops" to insure rapid and thorough processing notwithstanding the fineness of the material.

In the treatment of zinc ores where the furnace is fired on the lower hearths, furnaces as above described are particularly desirable in that oxidation may be gradually carried out on several or numerous of the hearths 95 instead of largely on one or two hearths, as has generally occurred in practice. Furnaces embodying this invention are adaptable to a wide variety of other uses such as calcining of fuller's earth, filtering clays, filtrol, limestone, dolomite, mercury ores, soda compounds, copper, iron, zinc, tin, antimony and arsenic ores, drying operations, etc. In these various operations the temperature 100 conditions within the furnace may be so controlled as to support combustion from the ores or material treated, or of course, the furnace may be fired externally.

While the invention has been described with respect to certain particular preferred examples which give satisfactory results, it will be understood by those skilled in the art after understanding the invention, that various changes and modifications may be made 115 without departing from the spirit and scope of the invention and it is intended therefore in the appended claims to cover all such changes and modifications.

What is claimed as new and desired to be 120 125 130

secured by Letters Patent of the United States is:

1. A roasting furnace comprising a plurality of superposed hearths, a rotatable shaft extending vertically of the furnace and carrying rabbling means, and additional means also carried by said rotatable shaft at one or more of the intermediate hearths for absorbing heat therefrom, said additional means providing a greater heat absorbing capacity at said intermediate hearths than is provided in the other hearths.

2. A roasting furnace comprising a plurality of superposed hearths, a rotatable shaft extending vertically of the furnace and carrying rabbling means, and additional means also carried by said shaft for absorbing heat at one or more of the intermediate hearths and transferring such heat to one or more of the lower hearths, said additional means providing a greater heat absorbing capacity at said intermediate hearths than is provided in the other hearths.

3. A roasting furnace comprising a multitude of superposed hearths, 12 or more in number, surrounded by a furnace wall, a rotatable air cooled shaft extending vertically of the furnace and carrying air cooled rabbling arms cooperating with the various hearths for advancing material under treatment successively over the various hearths down through the furnace from top to bottom, and additional means carried by said shaft for absorbing heat in the cooling air therein at one or more of the intermediate hearths.

4. A roasting furnace comprising a multitude of superposed hearths, 12 or more in number, surrounded by a furnace wall, a rotatable air cooled shaft extending vertically of the furnace and carrying air cooled rabbling arms cooperating with the various hearths for advancing material under treatment successively over the various hearths down through the furnace from top to bottom, additional means carried by said shaft for absorbing heat in the cooling air therein at one or more of the intermediate hearths, and means also carried by the shaft for discharging some of the air thus heated on to hearths where higher temperatures are desired.

5. A roasting furnace comprising a plurality of superposed hearths, a rotatable shaft extending vertically of the furnace and carrying rabbling means, said shaft and rabbling means having communicating cavities providing a circulatory path for cooling fluid, socket means independent of the rabbling members provided on said shaft at various hearths, and heat absorbing means detachably connected at said sockets and communicating with said circulatory path therethrough.

6. A roasting furnace comprising a plural-

ity of superposed hearths, a rotatable shaft extending vertically of the furnace and carrying rabbling means, said shaft and rabbling means having communicating cavities providing a circulatory path for cooling fluid, socket means independent of the rabbling members provided on said shaft at various hearths, heat absorbing means detachably connected at said sockets and communicating with said circulatory path therethrough, and gas discharging arms received by said socket means interchangeably with said heat absorbing means.

7. A roasting furnace comprising a plurality of superposed hearths, a rotatable shaft extending vertically of the furnace and carrying pluralities of rabbling arms cooperating with each hearth, and heat absorbing arms also carried by said shaft at one or more hearths, said heat absorbing arms and said rabbling arms being arranged alternately in spaced relationship around the shaft.

8. The method of operating a multiple hearth roasting furnace having air cooled rabble arms which comprises utilizing a part of the cooling air to absorb substantial quantities of heat in excess of that absorbed through said arms and the arm supporting means at one part of the furnace and to convey such heat to another part of the furnace.

9. The method of operating a multiple hearth roasting furnace having air cooled rabble arms which comprises utilizing a part of the cooling air to absorb substantial quantities of heat in excess of that absorbed through said arms and the arm supporting means at the mid-portion of the furnace and to deliver such heat at the lower part of the furnace.

10. A roasting furnace comprising a plurality of superposed hearths, a rotatable shaft extending vertically of the furnace and carrying rabbling means, said shaft and rabbling means having communicating cavities providing a circulatory path for cooling fluid, cooling fluid discharging arms also carried by said shaft, and said shaft having socket means for interchangeably receiving said rabbling means and said arms.

In testimony whereof we have signed our names to this specification.

EDITH MARY FOWLER,
Executrix of the last will and testament of
Edward J. Fowler, Deceased.

DUDLEY BAIRD.
